UNITED STATES PATENT OFFICE.

SAMUEL M. RYASON, OF KIRKWOOD, ILLINOIS.

TRAP.

1,152,980.

Specification of Letters Patent. Patented Sept. 7, 1915.

Application filed February 27, 1914. Serial No. 821,466.

To all whom it may concern:

Be it known that I, SAMUEL M. RYASON, a citizen of the United States, residing at Kirkwood, in the county of Warren and State of Illinois, have invented new and useful Improvements in Traps, of which the following is a specification.

This invention relates to traps and the object of the invention is to provide a trap having an entrance at all points of its circumference and wherein the bait is exposed from all sides of the trap.

Another object of the invention is to provide a simple and efficient "ever set" trap whose capacity is limited only by the sides thereof.

Further objects of the invention will appear as the following description is read in connection with the accompanying drawing, which forms a part of this application, and in which:

Figure 1 is a side elevation. Fig. 2 is a vertical sectional view on the line 2—2 of Fig. 1. Fig. 3 is a horizontal section on the line 3—3 of Fig. 1. Fig. 4 is a top plan view. Fig. 5 is a detail vertical sectional view on an enlarged scale.

Referring more particularly to the drawing, 1 represents a base of any preferred form here shown to be circular in outline and which has rising therefrom at predetermined circumferential intervals, from points adjacent the periphery of the base, suitable standards 2 which extend horizontally and radially at their upper ends and connect in the center of the top 3 with a connecting ring 4. This connecting ring has secured thereto a handle 5 by which the trap may be carried around. Connected to the standards at the point of their bend is a supporting ring 6 and secured to the standards intermediate their height are spaced supporting rings 7 and 8. The supporting ring 7 has secured thereto a plurality of bars which extend up over the ring 6 and secured to the standards intermediate their height are spaced supporting rings 7 and 8. The supporting ring 7 has secured thereto a plurality of bars which extend up over the ring 6 and connect with the ring 4 and radiating, as shown, to produce the top.

The ring 8 has extending inwardly there-

from a plurality of radiating loops 9 in which operate depending gate or door members 10 pivoted at their upper ends upon the rings 7. These gate or door members are limited in their outward movement by an annular flange 11 which is secured to the ring 8. The ring 7 being of greater radius than the inner periphery of the flange 11 causes the lower or free ends of the gate or door members to project inwardly so that the sharpened lower ends of said members will not be presented toward the animal entering the trap but will be presented toward the animal when within the trap.

The base 1 is provided with a central aperture closed by a hinged door 12 and covered by a foraminous cage 13 adapted to hold the bait. This cage may be made impregnable to the animal in the trap so that when the trap is used for catching large, carnivorous animals, live bait, such as sheep or calves, may be placed within the cage. When applying the bait, to the cage 13, the door 12 is swung in a position parallel with the bottom of the trap from its pivoted point, so that the bait can be forced upwardly into the cage and the door thrown backwardly to its normal position, the door when moving backwardly has its upper surface in sliding contact with the under surface of the bait.

The door or gate members are freely movable and have their pointed ends located a sufficient distance away from the base to prevent the animal, for which the trap is intended, crawling beneath the pointed ends, as will be readily understood. As the standards are separated from the lower ends of the gate or door members it will be seen that an unobstructive animal entrance is provided and that the bait can be viewed from all points in the circumference of the trap.

What is claimed is:

A trap comprising a base, standards rising therefrom, a pair of superimposed supporting rings secured to the standards, the side and top forming members secured to certain of the rings, pendent gate or door forming members having pointed ends and being pivoted to the upper of the supporting rings, the lower of said supporting rings being provided with an inwardly extending

flange, guiding loops connected to the under surface of said flange and radiating therefrom, whereby said pendent gate or door members may be limited in their outward movements by said flange and by said guiding loops in their inward movement, said gate or door members being pivoted to the door rings at suitably spaced intervals throughout the circumference of the sup-

porting rings and having their lower pointed ends arranged adjacent the base.

In testimony whereof I affix my signature in presence of two witnesses.

SAMUEL M. RYASON.
